United States Patent Office.

W. H. YOUNG AND L. YOUNG, OF BOSTON, MASSACHUSETTS.

Letters Patent No. 79,798, dated July 7, 1868.

IMPROVED CASTER FOR TRUNKS.

The Schedule referred to in these Letters Patent and making part of the same.

TO WHOM IT MAY CONCERN:

Be it known that we, W. H. YOUNG and L. YOUNG, of Boston, in the State of Massachusetts, have invented a new and useful Revolving Trunk-Caster; and we do hereby declare that the following is a full and exact description of the same, reference being had to the accompanying drawings, and to the letters of reference marked thereon, making a part of this specification, of which—

Figure 1 is an inside view of one corner of a trunk.

Figure 2 is a section of ditto.

Figure 3 is a side view of the caster and shank.

Figure 4 is a horizontal section of ditto.

The letter A represents the trunk; b, the metallic socket for supporting the caster-shank; c, the shank of the caster; d, its head; e, its shoulder; f, the caster or roller; g, the screw for retaining the shank in its place; and h, the metallic strip on the bottom of the trunk.

The nature and use of our invention is readily understood by examining the accompanying drawings; but in order that others may be enabled to manufacture and apply the same, we will proceed to explain it.

Casters for heavy trunks or boxes, as commonly made, are liable to be broken by rough usage, but our invention will stand rough usage without breaking. It has also this advantage over any trunk-caster now in use. It is made to revolve, the advantage of which is apparent.

We make use of a socket, b, as seen in figs. 1 and 2 in the drawings, placed in the corners in the inside of the trunk. This is made of metal, and so formed as to be fastened to the sides of the trunk by screws or otherwise, thereby strengthening the trunk, and the part holding the shank of the caster is cylindrical, and extends below through the bottom of the trunk and the metallic strip or corner-piece h.

On the inside a shoulder may be used at the bottom of the socket, where it rests upon the bottom of the trunk, to make the same tight.

The shank c is made of cast or malleable iron, or any suitable metal, and its form is seen in figs. 1, 2, and 3. The part below the bottom of the trunk is bent or curved, containing at the extremity, of course, the roll f, which is fastened in the usual way. Upon the shank, where it passes through the strip h into the socket, is a shoulder. The weight of the trunk partially rests on this shoulder. The shank, also, as it passes into the socket, begins to taper to the shoulder e, (see figs. 2 and 3,) where it fills the socket again, and forms the head d, resting against the upper part of the socket.

The advantage of this form of the shank within the socket is only to save friction. As the shank plays freely in the socket, a shoulder may be used on the shank, at about the point of the inner surface of the bottom of the trunk, filling the socket, so that a blow upon the roll will be distributed and received upon the shoulders of the shank, the sides, and the top of the socket, and the blow, being thus distributed, the shank and socket will sustain great pressure. At the shoulder e of the shank a screw, g, from the outside, passes through the socket and fits closely to the shank. This keeps the shank in place, and it cannot drop out, (see fig. 2.)

The shank being thus made and confined in the socket, turns or revolves very easily in any direction the trunk or box is to be moved. If one end of the trunk is raised by the hand and dragged along, the shank being curved and revolving, projects beyond the end of the trunk, and in whatever way the trunk is dragged, the roll performs its work.

The strip h also affords great protection to the bottom of the trunk. It helps to sustain the shank. It may decrease in thickness towards the end of the trunk, so that when the trunk is raised nearly on one end and is dragged along, it will slide more easily, and at the same time protect the bottom of the trunk. This form of caster can be applied to boxes and various kinds of furniture.

What we claim as our invention, and desire to secure by Letters Patent, is—

The revolving-shank c, with its head, d, the shoulder e, and the roller f, combined and arranged with the socket b, the screw g, and the strip h, substantially in the manner and for the purpose above set forth.

W. H. YOUNG,
L. YOUNG.
